UNITED STATES PATENT OFFICE.

THOMAS HOLMES, OF WASHINGTON, DISTRICT OF COLUMBIA.

IMPROVEMENT IN COFFINS.

Specification forming part of Letters Patent No. 42,659, dated May 10, 1864.

To all whom it may concern:

Be it known that I, THOMAS HOLMES, M. D., of Washington, District of Columbia, have invented new and useful Improvements in Deodorizing-Coffins; and I do hereby declare that the following is a full and exact description thereof, reference being had to the accompanying drawings, and to the letters of reference marked thereon, making a part of this specification.

The nature of my invention consists in the arrangement and construction of deodorizing-cases with pipes fitted on the inside of a coffin and on the under side of the lid of a coffin.

To enable others skilled in the art to make and use my invention, I will proceed to describe its construction and operation, as follows:

Figure 1 represents a perspective view of a coffin, showing the shapes of the cases and pipes. Fig. 2 represents a side elevation, showing the exact locations of the cases and pipes.

A represents the coffin, made of wood or metal.

B represents a groove in the inside of the coffin, extending down the center of its head-piece, in which a short horizontal and perforated pipe, C, is inserted, to which the leading vertical (three-eighths-of-an-inch) pipe D is attached, and extends down and along the center of the bottom of the coffin to a semi-circular-shaped case or box, E. This case is about five inches wide, ten inches long, and four inches high, made of metal, wood, or rubber, and has two perforated partitions, G, with

a center compartment, H, in which deodorizing substances are placed. A part of the obnoxious gases from the body pass into the perforated pipe C, thence down and along the pipe D to the case E, where they are deodorized, and from thence through the extended pipe, and are discharged at the foot of the coffin into the open air, freed of their obnoxious properties. On the inside of the lid of the coffin, just above the chest of the corpse, I have a conical-shaped elastic case, J, about four inches wide in diameter at the bottom, and contains an inside metallic box perforated, in which deodorizing substances are also placed and through which also a part of the gases from the corpse pass out and escape through the lid of the coffin, deodorized.

I have likewise on the inside of the lid of the coffin, near the foot, another semicircular-shaped case, K, having perforations L along the center of its bottom, and a perforated partition, M, and in the compartment P, I also put deodorizing substances, and the gases from the corpse enter through the perforations L and pass out likewise deodorized through the pipe R at the foot of the lid of the coffin.

What I claim as my invention, and desire to secure by Letters Patent, is—

The arrangement and construction of the deodorizing-cases, with their pipes arranged and constructed in the inside of a coffin, as herein described, and for the purposes set forth.

THOS. HOLMES.
